US00D624073S

(12) **United States Design Patent**
Peng et al.

(10) **Patent No.:** US D624,073 S
(45) **Date of Patent:** ** Sep. 21, 2010

(54) **RUGGED TABLET PERSONAL COMPUTER**

(75) Inventors: **Po-Hsuan Peng**, Miaoli (TW); **Yi-Chun Liao**, Taichung (TW)

(73) Assignee: **Getac Technology Corporation**, Hsinchu (TW)

(**) Term: **14 Years**

(21) Appl. No.: **29/351,441**

(22) Filed: **Dec. 5, 2009**

(30) **Foreign Application Priority Data**

Aug. 31, 2009 (CN) 2009 3 0209814

(51) **LOC (9) Cl.** 14-02

(52) **U.S. Cl.** D14/341

(58) **Field of Classification Search** D14/315–318, D14/341–346; D18/1, 2, 7, 11; 341/22, 341/23; 345/102, 104, 156, 163, 168; 361/679.09, 361/679.26, 679.27, 679.3; 206/320

See application file for complete search history.
